UNITED STATES PATENT OFFICE.

JEREMIAH BINGHAM, OF TOLEDO, OHIO, ASSIGNOR TO THE AMERICAN-NATIONAL COMPANY, OF TOLEDO, OHIO, A CORPORATION OF OHIO.

SHEET-METAL-WORKING MACHINE.

Application filed May 6, 1925. Serial No. 28,294.

To all whom it may concern:

Be it known that I, JEREMIAH BINGHAM, a citizen of the United States, and a resident of Toledo, in the county of Lucas and the State of Ohio, have invented a new and useful Sheet-Metal-Working Machine, which invention is fully set forth in the following specification.

This invention relates to metal working machines and particularly to machines for bending the edges of sheet metal.

Objects of the invention are to curl or roll an edge of a sheet metal strip of relatively light gauge in a simple and improved manner without liability of distortion; to provide a metal working machine which will readily bend without undesirable distortion the edge of sheet metal of light gauge; and to provide a machine of this character which will roll an edge of a sheet metal strip in the new and improved manner hereinafter described; and to provide a metal working machine having the new and improved features of construction, arrangement and operation hereinafter described.

The invention is shown by way of illustration in the accompanying drawings in which—

Fig. 1 is a top plan view with some of the parts broken away of a metal working machine embodying the invention; Fig. 2 is a section on the line 2—2 of Fig. 1; Fig. 3 is a section on the line 3—3 of Fig. 2; Fig. 4 is a view similar to Fig. 2 showing the clamping members separated; Fig. 5 is a section on the line 5—5 of Fig. 1; and Fig. 6 is a fragmentary perspective of the strip after the side edges thereof have been rolled and with the end portion bent at an obtuse angle.

The embodiment of the invention shown for illustrative purposes comprises a metal working machine or apparatus for curling or rolling the edge or edges of sheet metal strips of relatively light gauge. While it has been found to be a comparatively simple problem to curl the edges of sheet metal strips of relatively heavy gauge, the lighter metal strips present a more difficult problem for solution. An important factor to be taken into consideration in the latter case is the fact that the metal almost invariably buckles when curling is attempted so that it has heretofore been necessary in most instances to utilize fillers around which

the metal is curled; subsequently the fillers are usually removed in one way or another. This procedure necessitates considerable time and labor and is therefore quite expensive as well as being unsatisfactory for other reasons.

In the drawings, the machine is provided with a pair of relatively movable clamping members 1 and 2, the clamping member 1 being stationary and the clamping member 2 being moved toward and away from the member 1 by means of any suitable source of power. The clamping member 1 consists of a rectangular plate having on its upper surface a clamping block 3 which extends longitudinally thereof and is provided with rounded longitudinal edges 4. The width of the clamping block 3 is so chosen that the side edges of a sheet metal strip 5 placed thereon project to one side thereof, as indicated in Fig. 4.

Cooperating with the clamping block 3 for holding the sheet metal strip 5 in position is a second clamping block 6, which is fixed to and depends from the clamping member 2. The outer ends of the block 3 extend upwardly and outwardly, as indicated at 7, and the outer ends of the complementary block 6 are cut away as shown at 8, so that the two blocks interfit for firmly clamping the metal strip 5 therebetween. For permitting a slight movement between the block 6 and clamping member 2, screws 20 are fixed to the block 6 and are provided with heads 21 which are movable in sockets 22 in the member 2, and positioned between the parts 2 and 6 are coil springs 23 which serve to hold the block 6 normally distended and cushion the relative movement of the parts.

By constructing the clamping blocks with tapered, interfitting portions, as indicated, the metal strip 5 is not only firmly and securely held together for the curling operation but also enables the edges at the end portions of the strip to be curled when bent at an obtuse angle, thereafter when the curl or roll of the edge is completed the end portions of the strip may be bent at right angles without buckling or undesirably distorting the metal.

Mounted on the clamping member 1 on opposite sides of the block 3 are die blocks 9, which extend the entire length of the clamping member 1. The die blocks 9 are

movable transversely of the clamping member 1 concomitantly toward or away from the clamping block 3, being guided in such movement by guide members 10 (Fig. 5), 5 which project into grooves formed in the under surface of the die blocks 9. The die blocks 9 are provided on the inner faces thereof with longitudinally elongate die elements 11, which fit snugly into grooves 10 formed in the die blocks. The die elements 11 have grooves 12 which extend along the direction of the rounded edges 4 of the clamping block 3. The outer face of the die elements 11 protrude slightly beyond 15 the outer face of the die blocks and the clamping block 6 is formed with grooves 6', which are adapted to bear against the shoulders formed by the die elements as will hereinafter be described.

20 For concomitantly moving the die blocks 9 toward and away from the block 3, toggle levers 12 and 13 are pivoted at one end to longitudinally extending rods 14. The opposite ends of the levers 12 are pivoted to 25 brackets 15, which are set in recesses 16 in the die blocks 9, and the opposite ends of the levers 13 are pivoted to brackets 17. Connecting the rods 14 to the clamping member 2 are links 18, which are pivoted to 30 the rods at one end and to brackets 19 fixed to the clamping member 2 at the other end.

In the operation of the machine, a strip 5 is first placed on the block 3 with the side edges thereof bent slightly downwardly, as 35 indicated in Fig. 4, and with the opposite end portions bent upwardly to form an obtuse angle with the body portion in general to conform to the upturned end portions 7 of the block 3. When the clamping member 2 is forced downwardly, the block 6 first engages the sheet metal strip 5 and secures it firmly in position. Upon further movement of the clamping member 2, the 40 die blocks 9 are concomitantly moved inwardly toward the block 3 by means of the toggle mechanism above described, so that the down-turned side edges of the sheet metal strip are engaged by the slots or 45 grooves 12' in the die elements 11.

50 Further inward movement of the die blocks 9 causes the side edges of the metal strip to move around the inside of the grooves 12' thereby to curl or roll the edges. A slight upward buckling of the strip 5 55 may occur during this operation and in order to overcome this, the block 6 engages the upper surface of the strip 5, thus flattening it and also assisting in the final rolling operation. As indicated in Fig. 3, the rounded edges 4 are engaged by the edge 60 portions of the metal strip and aid in properly directing these portions to form the roll.

Thereafter by elevation of the clamping member 2 the several parts are returned to

normal position and the apparatus is in condition to receive another sheet metal strip for repeating the operation described.

A cardinal feature of this invention resides in the fact that the opposite side edges 70 of a sheet metal strip are rolled or curled simultaneously with the end portions of the strips bent upwardly to form an obtuse angle with the body of the strip. In this manner, after the edges are completely 75 rolled in the manner described, the end portions which have been bent to a considerable degree only have to be bent but a short way to form a right angle bend and this 80 bend may be effected without damaging or distorting the metal in the region of the bend. This is particularly important because heretofore in bending sheet metal strips having rolled edges it has been necessary to utilize fillers to prevent distortion 85 of the metal at the bend, but as will readily be apparent by this apparatus the strips may be bent without the aid of such fillers and the time and trouble required to effect these operations is reduced to a minimum. 90

It is to be understood that numerous changes in details of construction and arrangement may be effected without departing from the spirit of the invention, especially as defined in the appended claims. 95

I claim:

1. In a metal working machine, a pair of clamping blocks, said blocks being shaped to receive a sheet metal strip therebetween with the end portions of the strip bent to 100 form an obtuse angle with the body of the strip, means on one of said blocks and movable transversely of said strip for curling an edge thereof, and mechanism actuated by relative movement of said blocks for operating said curling means.

2. In a metal working machine, the combination of a pair of relatively movable members, a clamping block on one of said members having rounded edges, die blocks 110 on said last member movable transversely thereof, said blocks having longitudinally extending grooves, toggle levers connected at one end to the respective die blocks and at the other end to said last member, and means carried by the other of said members for concomitantly actuating said toggles to move said die elements in the direction of said block when said members are moved toward each other, whereby the opposite edges of the sheet metal strip are progressively forced into said grooves thereby to roll the same, the rounded edges of the block being adapted to cooperate therewith. 115

3. A metal working machine comprising a pair of relatively movable clamping members, a clamping block fixed to one of said members, a clamping block carried by the other of said members and having limited movement relatively thereto, said blocks be- 120 125 130

ing adapted to receive a sheet metal strip therebetween with the end portions thereof bent to form an obtuse angle with the body of the strip; die elements arranged on opposite sides of the longitudinal edges of said strip and adapted to engage and curl the edges thereof, and toggle means con-

nected to said clamping members, respectively, for conjointly actuating said die elements.

In testimony whereof I have hereunto signed my name to this specification.

10

JEREMIAH BINGHAM.
